MOP

Emil P. Gradinger, Kansas City, Mo., assignor to
 Golden Star Polish Manufacturing Company,
 Kansas City, Mo., a corporation of Missouri

Application November 20, 1933, Serial No. 698,795

7 Claims. (Cl. 15—147)

My invention relates to mops and more particularly to those of that character which include a mop fixture equipped with a removable hood and has for its principal object to provide a mop of this character wherein the hood is readily applied and securely retained on the fixture with the minimum amount of effort on the part of the user.

Other important objects of the invention are 10 to provide a sectionally hinged fixture which is spring tensioned when collapsed to apply the hood and which is automatically extended by torsion of the spring after the hood has been applied, and to provide stop engagement of the hinged sections when in extended condition for cooperating 15 with the spring in retaining the hood in taut condition on the fixture.

In accomplishing these and other objects of the invention, I have provided improved details 20 of structure, the preferred form of which is illustrated in the accompanying drawing, wherein:

Fig. 1 is a perspective view of a mop embodying the features of my invention.

Fig. 2 is a perspective view of the mop fixture. 25 Fig. 3 is a perspective view illustrating the application of the mop hood to the fixture.

Fig. 4 is a detail plan view of the fixture illustrating a portion of the handle in section to better illustrate the fixture connection with the 30 mop handle.

Fig. 5 is a fragmentary view through the mop fixture on the line 5—5, Fig. 4.

Referring more in detail to the drawing:

1 designates a mop fixture including a hood 35 supporting frame 2, a handle yoke 3 and a handle 4. The hood supporting frame includes heel and toe sections 5 and 6 that are hingedly connected together by the yoke 3 so that the frame may be collapsed for insertion into the mop hood, as hereinafter described.

The sections 5 and 6 are preferably formed of round spring wire material bent to substantially U-shape. The heel section 5 includes a slightly curved intermediate portion 7 and forwardly converging side bar portions 8 and 9 conforming in width and length to the rear portion of the hood. The side bar portions 8 and 9 are provided with inset portions 10 and 10' terminating in a plurality of tightly wound coils 11 and 12 to form hinge members 13 and 14, the ends of the inner coils being squared to provide abutment or stop shoulders 15 and 16.

The toe section has a more round and shorter intermediate portion 17 and rearwardly diverging 55 side bar portions 18 and 19 aligning with the

similar side bar portions 8 and 9 of the heel section.

The ends of the side bar portions 18 and 19 are reversely curved, as at 20 and 21, to terminate in tightly wound coils 22 to form hinge members 23 and 24 similar to the hinging members on the heel section previously described.

The ends of the terminal coils are squared off similar to the ends of the inner coils of the hinge members 13 and 14 to form stop shoulders 25 and 26 engaging the stop shoulders 15 and 16 respectively.

The yoke 3 is also formed of wire material and includes a bar portion 27 extending axially through the coils of hinged members 13, 14 and 23, 24 for hinging the heel and toe sections together, as clearly shown in Fig. 2. The yoke also includes laterally extending side bar portions 28 and 29 bearing against the outer coils of the hinged members 13, 14 to prevent outward lateral movement thereof that might be caused by the pitch of the coil winding when the sections are hinged relatively to each other. The side bar portions 28 and 29 terminate in inwardly and upwardly converging arms 30 and 31 having parallel 20 handle attaching portions 32 and 33 provided with inwardly bent ends 34 and 35, as shown in Fig. 4.

The handle 4 preferably consists of a wooden rod having diametrically spaced longitudinal grooves 36 at the end thereof for accommodating the attaching portions 32 and 33 of the yoke member and a transverse opening 37 at the upper ends of the grooves to receive the ends 34 and 35.

The portions 32 and 33 are retained in the 35 grooves of the handle and the ends 34 and 35 in the opening 37 by a sliding ferrule 38 that is adapted to be slid tightly over the arms of the yoke, as shown in Fig. 4.

In order to normally retain the heel and toe sections in alignment with each other and the stop shoulders 26 against the shoulders 16, the bar portion intermediate the hinged members is provided with a coil spring 39 having its ends bearing against the inner coils of the inner hinge members and provided with arms 40 and 41 having hooks 42 and 43 to respectively engage the opposite arms of the heel and toe sections at points adjacent the shoulders 15—16 and curved portions 21, 45 respectively.

In the construction thus far described, the spring 39 is tensioned prior to its application on the bar portion of the yoke so that the toe and heel portions are retained in alignment and with the shoulders 15—16 and 25—26 at the terminal 50 55

ends of the coils in abutting relation in order that the frame sections are retained in parallel relation to the plane of the surface being mopped.

The mop hood is shown to include upper and lower fabric sections 43 and 44 shaped to conform to the mop frame and which are stitched together about the periphery thereof, as at 45, to secure the sections together. The lower layer of fabric carries the usual mop fringe 46 and the upper layer of fabric is provided with a slot 47 to provide entrance for the sections of the fixture into the pockets 48 and 49 of the hood. The slot 47 is shaped to provide parallel side edges 50 spaced apart a sufficient distance intermediate its ends to freely pass the mop fixture and inwardly curved transverse edges 51 which extend over the hinge portion of the fixture a sufficient distance to prevent its marring furniture and the like, against which it may come in contact when the 20 mop is being used.

In applying a mop hood to the frame constructed and assembled as described, the hood is doubled back upon itself, as shown in Fig. 3, to expose the pockets 48 and 49 through the slot 47.

25 The toe and heel sections of the mop frame are then pivoted toward each other on the hinge bar of the yoke member so that the ends may be projected into the pockets, as clearly shown in Fig. 3.

Upon hinging movement by the frame sections, 30 the coil spring 39 is tensioned by tightening the winding thereof due to the connection of its ends with the respective sections. The spring is also placed under compression by hinge members 23 and 24 moving away from the hinge members 13 and 14, this camming action being caused by the pitch of the coils forming the hinge members.

After the frame sections have been inserted in the pockets, they are released and the torsion in the spring returns the sections into alignment with each other, thereby extending the mop tightly between since the forward and rear curved portions of the section wedge tightly into the ends of the pockets, as shown in Fig. 1.

The expansion of the spring also returns the 45 inner hinge members 23 and 24 into stopping engagement with the outer hinge members so that when the sections are in extended condition, the stop shoulders cooperate with the spring to prevent hinging movement of the sections.

50 The slight tension of the frame sections tends to retain the shape thereof and prevent them from being bent when the mop is being shaken free of dust or other material collected thereby.

To remove the hood, the hood may be simply 55 grasped by the fringe and a pulling force exerted on the handle which causes the frame sections to slip from the slot 47.

From the foregoing, it is apparent that I have 60 provided an improved mop fixture on which the hood is readily applied and which retains the hood in taut condition while the mop is being used.

What I claim and desire to secure by Letters Patent is:

1. A mop fixture including heel and toe sections, cam shaped hinge members on the sections, hinging means extending through said hinging members for securing the sections together, a coil spring on the hinging means having its ends engaging against the hinge members on one of said 70 sections to normally retain said hinge members in camming relation with the hinge members of the other section and having hooked shaped portions engaging the respective sections whereby the spring is compressed by camming action of the 75 cam members and torsioned incidental to hinging

movement of the sections and whereby the stored torsion and compression of the spring moves the sections into alignment with each other, and stop means on the hinge members for retaining the sections in alignment against torsion of the 5 spring.

2. A mop fixture including heel and toe sections formed of substantially U-shaped wire loops having ends terminating in coiled portions to form hinge members and terminating in stops with the stops on the coiled portions of the toe section normally engaging the stops on the coiled portions of the heel section for retaining the sections against movement in one direction, a pivot member extending through said coiled portions 15 for hingingly securing the sections together, a spring coiled about the pivot member and having hook shaped ends connected with the respective sections to torsion said spring incidental to hinging movement of the sections in the other direction and for returning the sections into stopping engagement with each other incidental to stored torsion of the spring.

3. A mop fixture including heel and toe sections having complementary cam shaped hinging portions, a yoke member having a bar portion extending through said hinge portions of the sections and having laterally bent end portions engaging the hinge portions of one of the sections to prevent lateral movement of said hinged portions on the bar portion of the yoke, a spring coiled about said bar portion of the yoke and having ends engaging the hinge portions of the other section, and hooks on the ends of the spring engaged with the respective sections, whereby the 30 spring is compressed by camming action of the hinge portions and torsioned incidental to hinging movement of the sections and whereby the sections are returned into alignment with each other incidental to stored torsion in the spring, and stop means on the hinged portions movable into stopping engagement by the spring for retaining the sections in aligned condition against torsion of the spring.

4. A mop fixture including heel and toe sections comprising substantially U-shaped wire loops having coiled end portions terminating in stops, a yoke member having a bar portion extending through said hinged members and having end portions engaging the coiled portions on one section to prevent outward lateral movement thereof on the bar portion, a spring sleeved on the bar portion and having ends bearing against the coiled portions of the other section to resiliently retain the terminal ends of said hinge members in abutting relation when the sections are in alignment with each other, and hook shaped ends on the spring engaging the respective sections for effecting torsioning of the spring incidental to hinging movement of the sections and for moving the sections into alignment with each other incidental to stored torsion of the spring.

5. A mop fixture including a pair of substantially U-shaped wire loop members having coiled end portions to form hinge members, a yoke member having a bar portion extending through said hinge members and having end portions engaging the hinge members on one of said loop members to prevent outward lateral movement thereof on the bar portion, a coil spring sleeved on the bar portion and having ends bearing against the hinge members of the other loop member to resiliently retain the terminal ends of said hinge members in abutting relation when the loop members are in alignment with each other, and hook 70 members 75

shaped ends on the spring engaging the respective sections for effecting torsioning of the spring incidental to hinging movement of the loop members and for moving the loop members into alignment with each other incidental to stored torsion of the spring.

5 6. A mop fixture including heel and toe sections, interengaging cam shaped hinge members on the sections, hinging means extending through 10 said hinge members for securing the sections together, a coil spring on the hinging means having its ends engaging against the hinge members on one of said sections and having hooked shaped portions engaging the respective sections whereby 15 the spring is compressed by camming action of the cam shaped hinge member on one section engaging the cam shaped hinge member on the other section and torsioned incidental to hinging movement of the sections, and stop means on the 20 cam shaped hinge members for normally retaining

ing the sections in alignment with each other against torsion of the spring.

7. A mop fixture including substantially U-shaped sections having coiled end portions to form hinging members, a yoke member having a bar portion extending through said hinged members and having end portions engaging the hinged members on one section to prevent outward lateral movement thereof on the bar portion, a spring sleeved on the bar portion and having ends bearing against the hinged members of the other section to resiliently retain the terminal ends of said hinge members in abutting relation when the sections are in alignment with each other, and hook shaped ends on the spring engaging the respective sections for effecting torsioning of the spring incidental to hinging movement of the sections.
